UNITED STATES PATENT OFFICE.

WALTER T. GODDARD, OF HAMILTON, ONTARIO, CANADA, ASSIGNOR TO LOCKE INSULATOR CORPORATION, OF BALTIMORE, MARYLAND, A CORPORATION OF MARYLAND.

INSULATOR.

Application filed October 1, 1921. Serial No. 504,665.

The invention relates to high tension insulators, and more particularly to improvements in the method of connecting metallic members to insulating sections.

5 The principal object of my invention, generally stated, is to provide a high tension insulator of maximum tensile strength, and the said insulator consisting of a plurality of members of porcelain or other dielectric material and a plurality of metallic sections secured together.

10 Another object of my invention is to provide an insulator in which the insulating and metallic portions are so connected as to eliminate or minimize strains due to the unequal expansion of the two elements under temperature changes.

15 A further object is to provide simple and effective means for securing the insulating sections together so as to simplify the connection between various parts of a multiple unit insulator.

20 The invention will be further and more fully set forth and particularly pointed out in the following specification.

25 In the drawings, wherein I have illustrated two embodiments of the invention,—

30 Figure 1 is a side elevation, partly in section, of a post insulator constructed in accordance with my invention.

Figure 2 is a transverse section on line 2—2 of Fig. 1.

Figure 3 is a section on line 3—3 of Fig. 2.

35 Figure 4 is a fragmentary section on line 4—4 of Fig. 1.

Figure 5 is a transverse section of a suspension insulator embodying some of the features of my invention.

40 Referring first to the embodiment shown in Figs. 1 to 4, inclusive, the numeral 1 designates generally a post insulator comprising a plurality of sections 2 and 3, preferably formed of porcelain. Each of the sections 3 is provided on the upper and lower faces thereof with annular concentric hub sections designated respectively 4 and 5. In each section, the hub portion 4 is of slightly less diameter than the hub section 5. Each of the sections 3, in the particular embodiment of the invention here illustrated, is of slightly less diameter than the section immediately below the same, and consequently the lower hub 5 of each section is made of equal diameter with the upper section 4 so 45 that the coating portions will correspond

in diameter. The hub sections 4 and 5 are each provided with openings 6 and 7. These openings intersect at points closely adjacent the upper and lower faces of the intermediate portion 8 of each section. The openings 7 are preferably radial openings and are cut from the inner face of the hub portions, while the openings 6 are substantially vertical and extend respectively from the faces of the hub sections 4 and 5. These openings, 50 which are preferably cylindrical in outline or section, may be formed in the insulating sections either in the so called leather dry state or after the insulator has hardened to the bone dry or white stage prior to firing. 55 The object and purpose of these openings will hereinafter be described.

The top or cap section 2 is of disk form and may be provided with the usual construction of groove 9, flange 10 and circular 60 groove 11 for securing the conductor thereto. On its under face the section 2 is provided with a hub 5 similar to the hubs 5 hereinbefore described in connection with the sections 3 and preferably equal in diameter to the hub 4 of the adjacent section 3.

65 In order to connect the section 3 to each other and to the section 2, I provide metal disks 12 of slightly greater diameter than the hubs 4 and 5. These metal disks are secured to each section, as will be now described. The disks 12 are each provided with a plurality of openings 13 corresponding in number and position to the openings 6 in each of the hub sections 4 and 5. In each of the openings 6 of the hub sections 4 and 5 I insert bolts 14, the end of each bolt being threadably received in a nut 15 which is adapted to fit within the openings 7. These nuts 15 preferably conform to the shape of the openings 7, as clearly indicated in the drawings. The projecting ends of the bolts 14 are adapted to be received in openings 13 provided in the coacting disks 12, and each disk is rigidly secured to its coacting hub section by means of nuts 17 which are threadably received on the outer ends of the bolts 14. Each disk 12 is also provided with a plurality of openings 18 adapted to receive the nuts 17 of the coacting section 3. The openings 6 are preferably made of sufficiently greater diameter than the diameter of the bolts 14 to permit lateral movements of the disk 12 and 100 105 110

the sections 2 and 3 relative to each other due to unequal expansion and contraction of the metal and porcelain under temperature changes.

- 5 The metal disk 12 secured to the hub 5 of the lower section 3 is preferably made of heavier metal than the intermediate disks 12 and is provided with means for securing it in operative position, such as the bolts 19.
 10 It may also be formed with a flange 20, and preferably serves as a base for supporting the insulator.

15 Each of the intermediate disks 12 is provided around the periphery thereof with a plurality of aligned openings 21 through which pass bolts 22 for rigidly uniting the various sections.

20 It will be readily apparent that the bolts 14, with the coacting nuts 15 and 17, secure the metallic disks 12 to each of the hub sections, and that by providing each disk with openings to receive the nuts 17 of the coacting section the two adjoining disks 12 will be in intimate contact with each other 25 and will provide a rigid connection between the adjacent sections. Since the faces of the hub sections are parallel to the faces of the disks 12, and since the openings 6 are of greater diameter than the diameter of the bolts 14, it will be apparent that the parts 30 may expand and contract without placing destructive strains upon the porcelain or other dielectric material of which the insulator is constructed.

35 In Fig. 5 I have illustrated the use of metallic plates connected to a suspension insulator in the same general manner as I have hereinbefore described with reference to the post insulator illustrated in Figs. 1 to 4. The suspension insulator of Fig. 5 is designated by the reference numeral 23. The insulator 23 is furnished with hub sections 24 and 25 in each of which I provide the radial openings 26 and the vertical openings 27. Bolts 14 with the nuts 15 and 17 are used to connect each hub section and the coacting metallic disk 27, said disks preferably being provided with a curved central boss 28 each of which coacts with 50 the curved end 29 of an eye-bolt 30.

What I claim is:—

1. A high tension insulator comprising an imperforate disk of insulating material having hub portions extending from the opposite faces thereof, a pair of substantially flat metallic disks cooperating with said disk of insulating material, and connecting means therefor comprising headed members seated in correspondingly formed openings 55 in said hub portions, said members being provided with projecting portions detachably secured to said metallic disks.
 60 2. A high tension insulator comprising a plurality of insulating units each of which is provided with an integral hub, the hubs

of adjacent units being adapted to cooperate, and means for connecting said, adjacent hubs, said means including headed members fitting in correspondingly formed recesses in the respective hubs, metallic plates 70 detachably connected to said headed members, and connecting means for said adjacent metallic plates.

3. A high tension insulator unit comprising a body member of insulating material 75 provided at opposite sides with flat faces, the body being formed with a cavity extending out to each flat face and being formed within the wall of each cavity with a series of radial openings and a series of other 80 openings communicating therewith and arranged in parallel relation to the longitudinal axis of the body, a flat disk disposed against and projecting beyond each flat side of the body, and securing members extending through the second named openings and one disk and having retaining means at both ends thereof, the retaining means at one end engaging within the first named openings and the retaining means at the other end 90 being located outwardly of the disks.

4. In a high tension insulator a unit formed as a body of dielectric material formed with a cavity and a series of radial openings in the wall of the cavity, said 95 openings communicating with the cavity, the body having a series of circumferentially arranged openings extending parallel to the longitudinal axis and in communication with said first named openings and extending out to one side of the body, a metal disk disposed against said side of the body, and securing members extending through the second named openings and the disk and provided with heads engaging exteriorly of 100 the latter, and retaining members having threaded connection with said securing members and located within said radial openings.

5. A high tension insulator comprising a 110 plurality of units of insulating material of disk form, concentric annular hubs formed on the upper and lower faces of said disk, each of said hubs being provided with openings therein, metallic disks provided with 115 openings opposing the openings in said hubs, and means, passing through the openings in each hub and the adjacent disks, for securing said metallic disk to said insulating disk and means for securing adjacent 120 metallic disks to each other.

6. A high tension insulator comprising a plurality of units of insulating material of disk form, concentric hubs formed on the upper and lower faces of said disk, a metallic disk of greater diameter than the diameter of said hub secured to each of said hubs by members housed within the same, and means for securing the disks of adjacent sections together. 125 130

7. In a high tension insulator, a unit formed as a body of dielectric material formed with a cavity and a series of radial openings in the wall of the cavity, said openings communicating with the cavity, the body having a series of circumferentially arranged openings extending parallel to the longitudinal axis and in communication with said first named openings and extending out to one side of the body, a metal disk disposed against said side of the body, and securing members extending through the second named openings and the disk and provided with heads engaging exteriorly of the latter, and retaining members having threaded connection with said securing members and located within said radial openings, the disk projecting beyond the side of the body engaged thereby and the projecting portion thereof being apertured for the reception of securing elements whereby the unit may be connected with an adjacent unit.
8. A high tension insulator comprising a plurality of units each formed as a dielectric body having a cavity at its top and bottom and provided with a plurality of radial openings communicating with each cavity and a plurality of openings parallel with the longitudinal axis and communicating with the first named openings, certain of the second named openings leading to the top and the remainder leading out to the bottom of the body, disks disposed against the top and bottom of the body, securing members passing through the second named openings and the adjacent disks and having heads located outwardly of the latter, and retaining members located within the first named openings and detachably connected with the securing members, the disks being apertured for the reception of the heads of the securing members of adjacent units.
9. In a high tension insulator, an insulating unit consisting of a disk of insulating material provided with a concentric annular hub, said hub being provided with a plurality of openings extending outwardly from the inner surface of said hub and having a plurality of openings within said hub portion, said last named openings intercepting the first named openings at approximately right angles, and means for securing said metallic disk to the insulating disk through the openings in said hub.

In testimony whereof I affix my signature.

WALTER T. GODDARD.
